D. S. JACOBUS,
METHOD OF AND APPARATUS FOR OPERATING STEAM BOILER ECONOMIZERS,
APPLICATION FILED NOV. 4, 1919.

1,416,353.

Patented May 16, 1922.

UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

METHOD OF AND APPARATUS FOR OPERATING STEAM-BOILER ECONOMIZERS.

1,416,353.

Specification of Letters Patent. Patented May 16, 1922.

Original application filed December 8, 1914, Serial No. 876,012. Divided and this application filed November 4, 1919. Serial No. 335,727.

To all whom it may concern:

Be it known that I, DAVID S. JACOBUS, a citizen of the United States, residing at Jersey City, in the county of Hudson and State of New Jersey, have invented certain new and useful Improvements in Methods of and Apparatus for Operating Steam-Boiler Economizers, of which the following is a specification.

10 The present invention relates to economizer practice and is designed to increase the efficiency of economizers and steam boilers, as well as the efficiency of the entire boiler and economizer system. In this connection, 15 the invention is also designed to remove dust, acid fumes and other solids from the waste gases. To that end, the invention consists in introducing moisture into the waste gases of the boiler after they have passed 20 one part or section of an economizer, and then passing the moistened and cooled gases over another part or section of the economizer and condensing thereon a portion of the introduced moisture.

25 This invention differs essentially from the introduction of moisture between a boiler and an economizer, in the following features. (1) The introduction of the moisture between sections of an economizer has a much 30 less deleterious effect on the draft resistance of the gases flowing through the boiler to the stack than where moisture is introduced between the boiler and the economizer as a whole. (2) The amount of heat absorbed 35 by the economizer is greater than it would be if the moisture were introduced between the boiler and the economizer. (3) Acid fumes may be condensed and removed between the economizer sections, and before the cooled 40 gases reach those parts of the economizer where the moisture would condense.

My present application is a division of my Patent No. 1,281,016, granted October 8, 1918.

45 My invention will best be understood by reference to the accompanying drawing, which is a diagrammatic side elevation, partially in section, of a steam boiler embodying my invention. Referring to the drawing, the numeral 1 designates a boiler of standard design, having a transverse steam and water drum 44, and fired with a chain grate stoker 3, the waste gases from the

boiler escaping through a flue in which the economizer and spraying devices are located. 55 For the purpose of describing one method of practicing the invention, I have shown a two-stage economizer with means for eliminating the air from the water before it is delivered to the high pressure stage. The 60 latter is designated generally by the letter A and is shown as located in a vertical flue 4, and as subjected to the hottest gases. The gases are made to flow in a downward direction over the tubes of the high pressure stage, and the flow of water through said stage is, in general, in the reverse direction of the flow of the gases. The high pressure stage of the economizer consists of a series of rows of tubes 6 expanded into 70 horizontal boxes or headers 7, said tubes having a slight inclination upward in the direction of the flow of the water. The tubes and boxes are preferably of wrought iron or wrought steel, to withstand the high boiler 75 pressure to which this stage of the economizer is subjected.

80 In the drawing illustrating the invention covered by my present application, a part of the low pressure stage of the economizer, designated generally by the letter C, is located in the lower part of the flue 4 below the high pressure stage A, and another part of the low pressure stage, designated generally by the letter C', is located in the flue beyond 85 where the water is sprayed through the gases. The low pressure part C comprises a series of tubes expanded into horizontal headers or boxes, and is similar in construction to the high pressure stage A. The tubes and boxes 90 of section C, if of wrought iron or wrought steel, are preferably coated both inside and outside with a protective coating, to prevent corrosion. The section C' of the low pressure stage is shown as consisting of two separated 95 banks 37 and 38 of vertical tubes connected to upper horizontal boxes 39, placed at different levels, and lower horizontal boxes 40, also placed at different levels. In this arrangement, the feed water enters pipe 41 100 and is distributed through the lower boxes 40, and thence flows upward through all of the tubes 37 and 38, and escapes from the upper boxes 39, through pipe 42, to the lower part of section C of the low pressure stage. 105 The water leaves the upper part of said stage

through a pipe 43 and is delivered to tank 17, from which it is fed to the lower part of the high pressure stage A by the pump 20. From the high pressure stage the water is 5 forced into the drum 44 of the boiler. In tank 17 are, preferably, perforated plates over which the water is made to flow, and by which it is broken up, to facilitate the disengagement and escape of air and gases 10 from the water, such disengagement being assisted by heating the water in the low pressure stage of the economizer, and, if desired; by maintaining a partial vacuum in the tank by any suitable means, such as the dry 15 vacuum pump 50; or the air and gases are permitted to escape through a relief valve 18. From the tank 17 the water is conducted by a pipe 19 to a feed pump 20, which forces it through a pipe 21 to the lower part of the 20 high pressure stage of the economizer. The water enters the lowermost header 7 and flows from side to side through successive 25 rows of tubes, and is delivered from the high pressure stage, through pipe 22, into the steam and water drum 44. This flow of the water through the high pressure stage of the economizer provides for a positive circulation and the passage through tubes all of which are inclined upward with reference to the direction 30 of flow of the water, and, in general, in the reverse direction of the flow of the gases.

It is well known that the rate of heat transfer from steam or liquids to a cooler surface, such as a tube wall, is much higher than the 35 rate of transfer from gases at the same temperature to the same cooler surface, and this principle is utilized by me in the operation of a steam boiler economizer. In the arrangement shown, I introduce water, or steam, or 40 both, into the gases between the high and low pressure stages of the economizer, one means for such purpose being a series of perforated pipes 23 connected to boxes located in the flue 4 below the high pressure stage A of 45 the economizer. As shown, the wall 4' of the flue 4 stops short of the bottom of the flue, so that the gases will flow through the passage below the wall 4' and upward to the opening into the flue in which the section C' 50 of the low pressure section of the economizer is disposed. The water or steam is delivered to the pipe 23 by any suitable means. The water may be supplied to the well 26 at the bottom of the flue 4 by a pipe 27, and pumped 55 from the well by a pump 28, through pipe 29, to the perforated pipes 23, from which it escapes in fine streams or spray. Any suitable means other than perforated pipes may be used for spraying the water.

60 In this arrangement, the water spray is introduced through the pipes 23 between the high pressure stage A and the section C of the low pressure stage. That part of the water which is not evaporated after spray-

ing through the gases and after passing over 65 the section C, collects in the well 26 in the lower part of flue 4, from which it is raised by the pump 28, through pipe 29, into the sprayer 23, and may thus be used over and over again, if desired. The gases, after passing over the section C, flow over the section C' of the low pressure stage, where the steam and water vapor is condensed, and flow down the inclined floor 45 into a well 46. The latter is connected by pipe 47 with the well 26 70 to equalize the water levels. The gases finally enter the induced draft fan 34 and from thence are delivered to the stack 35. The spraying of the economizer removes therefrom any condensation products from the 75 gases which would cause corrosion, and in case any acid is present, it is diluted and rendered harmless for ordinary conditions of operation. When the water becomes too foul for use, it may be drawn off, through a pipe 33, 80 and fresh water supplied to the well 26. When the water is circulated over and over again, a reagent to neutralize the acid fumes absorbed by the water may be added. Instead of circulating the water, the plant may 85 be operated by having a continuous supply of fresh water through pipe 29 and a continuous withdrawal through pipe 33, with a sufficient supply in the well 26 to maintain a 90 water seal for the pipe 47.

95 Doors 26' may be provided in the wall of flue 4, through which access may be had to the well 26 for the purpose of washing out the sediment through pipe 33, or the sediment may be shoveled out through the doors. 100

When the water is sprayed into the gases, as above described, the water will be partly 105 evaporated and will reduce the temperature of the gases, as a limit, to approximately 212° F., and this will produce a considerable volume of steam, which will be condensed as the gases pass over the last section of the low pressure stage of the economizer. This cooler stage of the economizer will be more active in absorbing the heat from the steam and moist gases than the same section would be in absorbing heat from relatively dry 110 gases.

115 As above stated, steam alone, or steam and water, may be used for moistening and washing the gases. In plants where the main steam motors are run non-condensing and in some plants where the main steam motors are run condensing, and where there are non-condensing auxiliary units, there is a surplus of exhaust steam, and this exhaust steam could be used in place of water. Steam would give additional heat to the economizer and would serve to throw down the cinders.

120 In addition to the advantage of an increased rate of heat transfer due to the addition of moisture to the gases, there is a 125

further advantage, in that the means described provide for the removal of soot, cinders and tar from the gases. In certain plants there is much trouble with the deposition of tar from the furnace gases on the coolest tubes of the economizer. This tar carries with it soot from the gases, the whole forming a pasty mass which cannot be effectively scraped from the tubes, and which 10 collects at the lower ends of the tubes and above the lowermost headers. By using a water spray or steam, in the manner described, the greater part of the tar and soot will be carried down and deposited in the 15 well 26. In the arrangement covered by my present application, there is a substantially greater increase in efficiency than in the arrangement shown in Fig. 1 of my prior application, due to the greater heat absorption, 20 by reason of the wetting of the surfaces of the tubes of section C of the low pressure stage of the economizer and the condensation of moisture in the section C'. Furthermore, as stated, the spraying of the economizer protects the same from corrosion by 25 removing from the surface thereof any products condensed from the gases which would tend to produce corrosion.

As has been stated, the drawings are 30 diagrammatic. Certain common and well known features, such as safety or relief valves for the economizers, have not been shown, in order to emphasize the features which apply more particularly to the invention. Regulating the supply of makeup 35 water and maintaining the proper levels of water in the hot wells, as well as regulating the water levels in the mixing tanks or heaters, may be carried out in many well known 40 ways. These are operating features aside from the principles of my invention which I have described.

While I have herein shown and described one modification of my invention, I do not 45 desire to be limited to the exact arrangement shown and described, but seek to cover, in the appended claims, all those modifications which come within the true spirit and scope of my invention.

50 What I claim and desire to secure by Letters Patent of the United States is:

1. The herein-described method of operating a steam boiler, consisting in passing the 55 gases over one part of an economizer, then passing them over another part of the economizer, and spraying water over the latter part of the economizer as the gases pass thereover.

2. The method of operating a two-stage 60 economizer which consists in passing the gases over the two stages in succession and

spraying the gases while passing over the second stage.

3. The herein-described method of operating a steam boiler economizer which consists 65 in passing the gases over a part of an economizer, then passing them over another part of the economizer and spraying the gases while passing thereover, and then passing the gases over a further cooler and un- 70 sprayed part of the economizer.

4. The method of operating a steam boiler comprising an economizer having high and low pressure stages, and the low pressure stage of which comprises two sections, which 75 consists in passing the gases over the high pressure stage, then passing them over the first section of the low pressure stage and spraying the gases while passing thereover, and then passing the sprayed gases over the 80 second section of the low pressure stage.

5. The method of operating a steam boiler having an outlet flue in which an economizer is set which consists in adding to a liquid a 85 corrosion-preventing chemical reagent and spraying the reagent-containing liquid over the cooler portion of the economizer to wash off any corrosive materials and thereby prevent corrosion.

6. A steam boiler plant having a waste 90 flue and an economizer in said waste flue divided into separated parts, and means for spraying water into the gases over one of said parts.

7. A steam boiler having a waste flue for 95 the products of combustion, an economizer in said waste flue divided into separated parts, means for spraying water into the gases over one of said parts, and another part of the economizer over which the moist 100 gases thereafter flow.

8. A steam boiler plant having a waste flue comprising a vertical portion, an economizer disposed within said flue and divided into two stages, one stage of which comprises 105 two sections, one stage and only one of the sections of the other stage being disposed within the vertical portion of said flue, and means for spraying the gases while passing over said section in said flue.

9. A steam boiler plant having a waste flue comprising a vertical portion, an economizer comprising high and low pressure stages, the low pressure stage comprising two sections, the high pressure stage and 115 only one section of the low pressure stage being disposed within the vertical portion of said flue, and means for spraying the gases during their passage over said low pressure section.
